BED

William Charles Bornhuetter, Maplewood, N. J.

Application November 20, 1943, Serial No. 511,008

4 Claims.

(Cl. 5—288)

This invention relates to improvements in furniture and more specifically to beds.

One of the important features of the invention resides in a bed construction in which the parts are standardized to make them interchangeable to facilitate the ready assembly of different sizes and designs of beds, couches and like articles of furniture.

Another feature of the invention is to provide a bed in which the head, foot, and side rails are all separable from the corner supporting legs which enables a furniture dealer to maintain a stock of various sizes and designs of rails and to readily assemble a bed to suit the needs and artistic taste of a customer.

A further object of the invention is the provision of a bed embodying a strong and rigid separable lock connection between the ends of the rails and the corner legs.

A still further feature of the invention resides in a bed in which the headboard is interchangeable with the headrail to facilitate the changing of the design of headboard, thus making it unnecessary for the owner of the bed to purchase an entire new bed when the color scheme or style of bedroom furniture is changed.

Other novel features of the invention will become apparent as the following specification is read in conjunction with the accompanying drawings, in which,

Figure 1 is a perspective view of my improved bed in set-up position.

Figure 2 is an enlarged vertical sectional view on the line 2—2 of Figure 1.

Figure 3 is an enlarged vertical sectional view on the line 3—3 of Figure 1.

Figure 4 is an enlarged horizontal sectional view on the line 4—4 of Figure 1.

Figure 5 is an enlarged horizontal sectional view on the line 5—5 of Figure 1.

Figure 6 is an enlarged detail vertical sectional view on the line 6—6 of Figure 1.

Figure 7 is a detail horizontal sectional view on the line 7—7 of Figure 6.

Figure 8 is a fragmentary collective perspective view of the parts of the bed in separated position.

Figure 9 is a vertical sectional view illustrating a modification of the invention.

Figure 10 is a perspective view of the locking key member embodied in the construction shown in Figure 9.

Referring to the drawings by reference characters, the numeral 10 designates my improved bed in its entirety which includes identical side

rails 11—11, a head rail 12, a foot rail 13, and four corner legs 14 to which the aforesaid rails are releasably locked in a novel manner to be presently described. The side rails 11—11 are of a length to suit the user of the bed, that is, if the bed is intended for a child, the side rails will be relatively short, if for a medium height adult, they may be of average length, while for an exceptionally tall person the same may be of a length greater than average. Also, the head and foot rails may be of a length to meet the requirements of a single, three quarters, or double bed to suit the needs of the user.

The rails 11—11, 12, and 13 are of like construction and have straight ends. Preferably the rails are made of metal channel stock and each includes a relatively wide vertical riser 15, a top inwardly extending flange 16, and a relatively narrow inwardly extending bottom flange 17. A portion of the riser 15 is shown as inwardly offset to form a recessed portion 18 in which an ornamented plastic or wood panel (not shown) may be countersunk for decorative purposes. The ends of each rail 11—11, 12, and 13 are provided with metal locking plates 19—19 which are welded, riveted or otherwise fixedly secured to the inner side of the riser 15. Each plate extends beyond the end of the rail to provide a tongue portion 20 having a slot 21 extending downwardly from the top edge thereof. The free end of each tongue portion 20 is rounded as at 23 to facilitate the insertion into its related leg 14 as will be presently explained.

Each corner leg 14 is preferably constructed of metal and is of hollow construction which is open at its top and closed at its bottom. The leg 14 is square in cross section and has an upper vertical body portion 24 and a lower downwardly tapered portion 25. Vertical elongated slots 26 are provided in two adjacent right angular side walls of the upper body portion 24, the width and length of said slots being equal to or slightly greater than the thickness and height respectively of the tongue 20 which it receives. The slot 26 in each wall is outwardly offset with respect to its longitudinal mid-portion so that the joints between the ends of the rails and the legs will be adjacent the outer exposed side faces of the legs as best illustrated in Figures 1, 4 and 5.

Associated with the respective legs at the foot of the bed 10 are locking key members 27 and associated with the legs 14 at the head of said bed are locking key members 28. Each locking key member 27 and 28 comprises a metal key body composed of flat right angularly disposed

key portions 29—29 to which a flat cap 30 is fixedly secured. The cap 30 is preferably made of plastic for decorative purposes and covers the open top of the leg when the locking key is in locking position therein. The key portions are of a width equal to the respective widths of the inner adjacent walls of the leg which they are adapted to engage as shown in Figure 4.

To effect a locking of adjacent ends of two right angularly disposed rails together, the tongues 20—20 of the rails are respectively inserted through the slots 26—26 of the leg 14, whereupon the key member 27 or 28, depending upon whether the connection is between the foot or head rail and the side rails, is inserted downwardly through the open top of the leg, whereupon the key portions 29—29 respectively enter the slots 21—21 of the tongues 20—20 as best seen in Figures 2 and 3. The flat cap 30 rests upon the top of the leg when it is fully inserted therein to close the same and impart decoration to the corner leg connection. Thus, when all four rails are similarly connected to their related corner legs, the bed will assume a rigid set-up position as illustrated in Figure 1, wherein the straight ends of rails abut the exterior surfaces of the legs to which they respectively abut to impart added bracing of the joints.

The locking key members 28—28 are provided with upwardly extending pins 31 which are round in cross section. Each pin 28 is preferably made of metal and extends through an opening 32 in the cap 30. The lower end of the pin 31 is disposed in the crotch between the right angularly disposed key portions 29—29 to which it is welded or otherwise permanently secured as at 33.

The upwardly extending portions of the pins 31—31 respectively enter sockets 34—34 provided in a headboard 35. The sockets 34—34 open through the bottom of the headboard 35 and are so spaced to receive the respective pins, the bottom of the headboard resting upon the top flange 16 of the head rail 12 to relieve the weight of the same from the pins. The pin and socket connections between the head corner legs and the headboard are snug and rigid to prevent loose play therebetween.

In Figures 9 and 10 of the drawings, I have illustrated a modified form of my invention wherein the head, foot and side rails are each provided at their ends with a pair of spaced superposed locking plates 19a. The extending tongue portions 20a of the locking plates are provided with slots 21a. The corner leg 24a has two of its adjacent sides each provided with a pair of spaced vertical slots 26a—26a through which the respective tongues 20a extend. The locking key member 27a for locking the pairs of locking plates of two adjacent rails is similar in construction to the locking key member 27 with the exception that the right angularly disposed key portions 29a—29a are provided with vertical slots 36 to receive the upper locking tongues 20a, which slots are brought into registration with the slots 26a during the initial assembly of the leg 24a and the ends of adjacent rails to be connected thereto. The slots 36 are of a length and width slightly larger than the respective height and thickness of the locking tongue 20a which they receive. When the locking key member 27a is fully inserted into the leg 24a the lower edge of the key portions 29a interlock with the walls of the slots 21a of the lower locking tongues 20a while the key portions 20a directly above the

slots 36 enter the slots 21a of the upper locking tongues and interlock with the walls thereof.

The top edge of each of the legs 24 and 24a is provided with a struck-in portion 31 to facilitate the insertion of an instrument beneath the cap 30 to pry the locking key member upwardly when it is desired to disconnect the rails from the legs.

From the foregoing description and accompanying drawings, it will be understood that various size beds may be rapidly assembled by a furniture store by maintaining a stock of head, foot, and side rails of different lengths. Also various designs of furniture may be made by a varied stock of rails such as twin beds, lounges, couches, and other articles of bed-like furniture. Further, by reason of the removable connection of the headboard with the head corner legs, various styles of headboards may be interchangeably associated with the bed which enables a salesman to display a variety of bed styles to a prospective customer, and which permits the user of a bed to change the style from time to time to meet his or her artistic taste and to conform to the period furnishings of a bedroom.

It will be understood that should the purchaser of a bed desire a foot board, the foot corner legs may also be provided with locking key members 28 and the foot board with pin-receiving sockets 34.

While I have shown and described what I consider to be the preferred embodiment of my invention, I wish it to be understood that such changes in design and materials as come within the scope of the appended claims may be resorted to if desired, without departing from the spirit of the invention as set forth in the appended claims.

Having thus described the invention, what I claim as new and desire to secure by Letters Patent is:

1. In a bed construction, a tubular supporting leg having a pair of vertical slots therein spaced at approximately ninety degrees, a pair of horizontal rails arranged substantially at right angle to each other, locking tongues carried by said rails and extending through the respective slots, a single key member insertable through the top of the tubular leg, and interlocking means between the key member and said tongues for rigidly connecting the rails and leg together.

2. In a bed construction as set forth in claim 1 in which the interlocking means comprises a pair of right angularly disposed key portions on the key member having interfitting engagement with slots provided in the respective locking tongues.

3. In a bed construction, a tubular supporting leg having at least two contiguous flat side walls disposed at right angle to each other, said side walls, each having a vertical slot therein, a pair of right angularly disposed horizontal rails having straight ends respectively abutting the flat side walls, a locking plate fixedly secured to the inner side of each rail, each locking plate having a tongue portion extending beyond the straight end of its related rails, the tongues of the locking plates extending through the respective slots, and a single locking element slidably inserted downwardly through the tubular leg into locking engagement with both of said locking tongues.

4. A bed comprising, in combination, four tubular corner legs, each corner leg having flat contiguous right angularly disposed exterior surfaces, two adjacent of said surfaces having a vertical slot therein, a pair of side rails, a pair

of end rails, each of said side and end rails having a vertical riser portion and upper and lower inwardly extending flange portions integral with the riser portion, the adjacent ends of a side rail and an end rail flatly abutting the angularly disposed exterior surfaces of a corner leg, locking tongues carried by the vertical riser portions of

said rails and extending through the respective slots, a single key member insertable through the top of the tubular leg, and interlocking means between the key member and said tongues for rigidly connecting the rails and leg together.

WILLIAM CHARLES BORNHUETTNER.
